FIG. 3.

Hamilton Neil Wylie
Inventor
By *John G. Lamb* Atty.

UNITED STATES PATENT OFFICE.

HAMILTON NEIL WYLIE, OF EDINBURGH, SCOTLAND.

METAL STRUT FOR AIRCRAFT.

1,364,538.

Specification of Letters Patent.

Patented Jan. 4, 1921.

Application filed August 22, 1919. Serial No. 319,244.

To all whom it may concern:

Be it known that I, HAMILTON NEIL WYLIE, major in the Royal Air Force, a subject of the King of Great Britain, residing at 5 16 Comiston Drive, Edinburgh, Scotland, have invented certain new and useful Improvements in Metal Struts for Aircraft, of which the following is a specification.

This invention relates to aircraft members that are made from thin metal and that are subjected mainly to thrust.

The invention consists in designing such members so that the application of the load on a member causes the member as a whole, 15 or causes its component parts to bend in a predetermined manner such that its less rigid parts are subjected to relatively light compression stress or to tension stress.

By this arrangement the stresses can be 20 localized on the parts of the member best able to withstand them, and the edges along which the plates, strips, or bars, forming the member, are connected together, or the parts of them that are only slightly curved in the 25 cross-section of the member are relatively lightly stressed.

By this arrangement also any bracing members which may be used in the construction of the member may be adapted to resist 30 tension only.

The invention is illustrated in the drawings accompanying this specification, in which Figure 1 is a cross-section of a streamline strut, Fig. 2 shows the same strut in elevation, and Fig. 3 shows a modified form of 35 strut in elevation.

Referring now to the drawings, the invention is shown in its application to interplane struts and other struts in the wind stream, in 40 Figs. 1 and 2, in which A is a thin plate bent with relatively great curvature at B to form the leading portion of the strut, which is of streamline cross-section, and therefore only slightly curved on the side 45 portions at C. D is a web of channel cross-section connected through packing strips M to the plate A by any ordinary means. With the cross-section shown, the plate at B is enabled by its curvature to develop higher 50 compression stress without buckling than at C, where the plate is almost flat and where the edges occur.

According to the invention, the load is applied along an axis through L which lies be-

tween the centroid G of the metal in the 55 cross-section and the leading edge B. The ends of the strut will be suitably designed in accordance with the usual practice for the load to be effectively applied at the ends of the axis through L. The method of forming 60 the ends of the strut for this purpose, however, forms no part of the invention.

The centroid G is determined for that part of the complete cross-section of the strut which functions in resisting stresses. For 65 example, in Fig. 3 the fairing (not shown in the drawing) which may be applied to complete the strut may be of such light and non-resistant material, such as papier mâché, that it adds no appreciable strength, and in this 70 case the centroid G is that of the sheet metal portion of the strut only.

In Figs. 1 and 2 are shown a form of cross-section of strut which comprises a fore part of sheet steel A and a rear part N 75 which may be of lighter material such as aluminium, the two parts A and N being connected together as shown. The fore part A contains a packing piece M and within the said packing piece a web of 80 channel cross-section D is attached. Owing to the projecting edges of the fore part A and the web of the channel D a groove is left into which the leading edge of the fairing N is received and positioned. Formers 85 O at suitable distances apart are attached to the channel D and fore part A by a locking pin P, and the fairing N is riveted to these formers which retain the fairing in position. The fairing N is anchored at each 90 end of the strut by any attachment preventing longitudinal movement relatively to the fore part A and as illustrated by means of a shoe R. In the case of struts of this and similar forms, the area of an element 95 of the cross-section is multiplied by the elastic constant of that element in determining the centroid G of the cross-section. The load will then be applied to the strut along an axis which is in front of the centroid. 100

In the form of construction shown in Fig. 3 stiffness is given to the strut about the transverse axis of the cross-section by a tension member E attached at its ends to the top and bottom of the strut and held 105 away from the web of the strut at intervals in its length by truss pieces F. By placing the axis of loading near to the leading edge

B as hereinbefore described, the member E is subjected to tension by the application of load to the strut.

When the strut is relatively flexible about its transverse axis, it has been found advantageous to make the truss pieces F stiff and to connect them rigidly to the strut and also to connect the tension member E to the truss pieces. By this means, the lengths of strut between adjacent truss pieces have their ends fixed in direction by the truss pieces and are thus enabled to carry a much higher load.

When this strut Fig. 3 is used in the wind stream and provided with a fairing as illustrated in Figs. 1 and 2, the tension member could suitably form a support for the trailing edge of the fairing.

It has been found advantageous in many cases to form the fairing of struts from thin aluminium sheet. This sheet, however, is liable to buckle and wrinkle when the strut is shortened by the application of the load. By causing the strut to bend slightly with its leading edge in compression in accordance with my invention the rear part of the fairing is relieved of its compression stress and even put in tension, but the portions of the fairing adjacent to the strut proper are liable to be still in compression. To prevent these portions from buckling in an irregular manner, it has been found advantageous to form fore-and-aft flutings K in these parts of the fairing.

35 This arrangement is shown in Fig. 2. N is the fairing composed of thin aluminium sheet. The portions of the fairing extending from the web D to the lines XX are in compression and are formed with flutes K, while the portion H of the fairing at the rear of the lines XX is in tension owing to the bending action of the strut.

Most of the members hereinbefore described are suitable for other than aircraft structures. They are particularly suitable for structures in which lightness is essential, such as long span conveying and transporting structures. It is to be understood that the scope of the invention is not limited to members for aircraft.

What I claim as my invention and desire to secure by Letters Patent is:—

1. An aircraft strut comprising in combination a thin metal strip bent upon itself in the direction of its length with a relatively great curvature to compose the forward portion of a streamline body the rear edges of said strip being at a distance apart, a web of thin sheet metal located between and connecting the said rear edges of said bent forward part, means for fixing said edges of said web to said rear edges of said forward part and a stress resisting member connected to said rear edges of said forward bent part to form the trailing part of the

structure, said strut structure being adapted for the application of the load in a plane parallel to the centroid axis of the strut and between said axis and the leading part of said bent forward part.

2. An aircraft strut comprising in combination a thin metal strip bent upon itself in the direction of its length with a relatively great curvature to compose the forward portion of a streamline body, the rear edges of said strip being at a distance apart, a web of thin sheet metal located between and connecting the said rear edges of said bent forward part, means for fixing said edges of said web to said rear edges of said forward part, a stress resisting member comprising a strip of sheet material bent longitudinally upon itself to form a fairing to compose the trailing part of the structure, means for attaching the forward edges of said fairing to the rearward edges of said bent forward part and means for connecting said fairing to said bent forward part at each end of the strut to prevent longitudinal movement of said fairing relatively to said bent forward portion, said strut structure being adapted for the application of the load in a plane parallel to the centroid axis of the strut and between said axis and the leading part of said bent forward part.

3. An aircraft strut comprising in combination a thin metal strip bent upon itself in the direction of its length with a relatively great curvature to compose the forward portion of a streamline body, the rear edges of said strip being at a distance apart, a web of thin sheet metal located between and connecting the said rear edges of said bent forward part, means for fixing said edges of said web to said rear edges of said forward part, a strip of thin sheet metal such as aluminum bent longitudinally upon itself to form a fairing to compose the trailing part of the structure, the relatively slightly curved forwardly extending sides of the fairing having flutings spaced apart and extending in a forward and rearward direction to prevent said side parts of the fairing from buckling in an irregular manner, means for attaching the forward edges of the fairing to the rearward edges of the bent forward part and means for connecting said fairing to said bent forward part at each end of the strut to prevent longitudinal movement of the fairing relatively to said bent forward part, said strut being adapted for the application of the load in a plane parallel to the centroid axis of the strut and between said axis and the leading part of the said bent forward part.

4. An aircraft strut comprising in combination a thin metal strip bent upon itself in the direction of its length with a relatively great curvature to compose the forward portion of a streamline body, the rear edges of

said strip being at a distance apart, a web of thin sheet metal of channel section having its flanges extending rearwardly and located between said rear edges of said bent 5 forward part, means for fixing the flanges of said channel section web to the interior facing surfaces near the rear edges of said bent forward part and a stress resisting member connected to said rear edges of said forward bent portion to form the trailing part of the structure, said strut structure being adapted for the application of the load in a plane parallel to the centroid axis of the strut and between said axis and the leading 15 part of said bent forward part.

5. An aircraft strut comprising in combination a thin metal strip bent upon itself in the direction of its length with a relatively great curvature to compose the forward portion of a streamline body, the rear edges of said strip being at a distance apart, packing strips one on each inner surface of 20 the side members of the bent forward part and near the rear edges thereof, a web of thin sheet metal of channel section having 25 its flanges extending rearwardly and located between the rear edges of said bent forward part in contact with said packing strips and extending rearward of same to form

grooves between the rear edges of said bent 30 forward part and the rear edges of said flanges of said channel section web, means for fixing the flanges of said channel section web and said packing strips to the interior facing surfaces of said bent forward part, 35 a strip of thin sheet metal bent longitudinally upon itself to form a fairing to compose the trailing part of the structure, the relatively slightly curved forward edges of said fairing fitting into said grooves of said 40 bent forward part, means for fixing the forward edges of said rearward fairing to said bent forward part, shoes for connecting said fairing to said bent forward part at each end of the strut to prevent longitudinal 45 movement of said fairing relatively to said bent forward part and means for applying the load to the strut structure in a plane parallel to the centroid axis of the strut and between said axis and the leading part 50 of said bent forward part.

In witness whereof I have hereunto set my hand in the presence of two witnesses.

HAMILTON NEIL WYLIE.
